CLAIM

The ornamental design for a child resistant triangle container, as shown and described.

DESCRIPTION

FIG. 1 is a perspective view of a child resistant triangle container showing our new design;

FIG. 2 is a rear perspective view thereof;

FIG. 3 is a top view thereof;

FIG. 4 is a bottom view thereof;

FIG. 5 is a front view thereof;

FIG. 6 is a rear view thereof;

FIG. 7 is a right-side view thereof;

FIG. 8 is a left-side view thereof;

FIG. 9 is a left-side perspective view of the child resistant triangle container shown in FIG. 1, in a partially opened orientation;

FIG. 10 is a top view thereof;

FIG. 11 is a bottom view thereof;

FIG. 12 is a front view thereof;

FIG. 13 is a rear view thereof;

FIG. 14 is a right-side view thereof;

FIG. 15 is a left-side view thereof; and,

FIG. 16 is a left-side view thereof, in a fully opened configuration.

1 Claim, 14 Drawing Sheets
